HAIR TENSOR

Judd E. Edwards, Belvidere, and William H. Noble, Evanston, Ill., assignors, by mesne assignments, to Master Grip-O-Matic, Inc., Belvidere, Ill.

Application May 29, 1936, Serial No. 82,664

24 Claims. (Cl. 132—33)

This invention relates to hair tensors, i. e. devices in the use of which the hair is wound on a spindle substantially parallel to the scalp, the spindle being held in a clamp close to the head to prevent unwinding. Such devices are employed when giving a permanent wave to the hair.

The general object of the invention is to provide an improved device as a whole and improvements in the separate parts thereof, which device is more convenient to manipulate, more effective in putting the hair under tension, and is lighter, cooler and safer than prevailing equipment.

Other objects are:

To provide a hair clamp consisting essentially of only three parts, i. e. the two jaws and a cam, but so designed that the jaws may be adjustably clamped to accommodate tresses of hair of different thickness;

To provide the jaws of such a clamp with a special facing to prevent leakage of hot vapor through the clamp, despite such variations in thickness, and to prevent baking an objectionable kink or bend in the hair when the clamp becomes hot;

To provide a hair clamp in which the auxiliary jaw is normally held open at a considerable angle, but which may be closed readily and automatically locked by a movement of a finger and thumb of the hand in which the clamp is held;

To provide a clamp of this character with a special heat insulating plate or "condenser" having a toothed edge which separates the hair into small strands so that the condensed steam and other hot fluids cannot readily run down the hair onto the clamp. It also condenses the vapor and serves as an improved cooling element.

To provide an improved spindle on which the hair may be wound by securely clamping the ends of the hair and maintaining the clamp in position mechanically and adjustably, leaving the hands free to rotate the spindle in either direction and to tension the hair effectively.

To provide such a spindle with an improved and invisible clutch device for permitting a final tensioning of the hair without danger of slippage.

To provide a plurality of cooperating devices capable of being fitted together to form a complete unit which is small, light, efficient and of moderate cost.

Other objects and advantages will be apparent from the description hereinafter given of one embodiment of the invention.

In the accompanying drawing:

Fig. 1 is a top plan view of the device;

Fig. 2 is an end elevation thereof;

Fig. 3 is a front elevation thereof;

Fig. 4 is a similar elevation with the jaws separated;

Fig. 5 is a side elevation of the spindle with its clamping member in open position;

Fig. 6 is an enlarged sectional elevation on the line 6—6 of Fig. 4;

Fig. 7 is an elevation of the resilient notched plate or condenser;

Fig. 8 is a bottom view of the same bent to illustrate the method of assembly;

Fig. 9 is a bottom view of the clamp;

Fig. 10 is an enlarged elevation of the clamp with the upper plate removed and certain parts broken away;

Fig. 11 is an enlarged elevation partly in section of one end of the spindle;

Fig. 12 is an enlarged elevation of the other end thereof;

Fig. 13 is an end view of a hollow headed pin;

Fig. 14 is a section on the line 14—14 of Fig. 10.

Fig. 15 is a plan view of a rubber liner; and

Fig. 16 shows a modified form of cam.

The complete device, shown in the drawing, is made up, generally speaking, of two units or 20 separate parts. One unit comprises a clamp for clamping the hair near the scalp. The other unit comprises a spindle on which the hair is wound while maintaining it under tension. During the winding operation, the spindle approaches the 25 clamp and is eventually fitted into brackets on the clamp and thereafter turned and held against reverse rotation to maintain the hair under tension. Before beginning the operation a felt pad having a slit in it is positioned between the scalp and the clamp, the strands of hair passing through said slit.

Referring to the parts more in detail, the clamp, which is indicated as a whole by 10, comprises a lower jaw and a smaller upper jaw hinged thereto. The lower jaw, which may be called the receiver member, is built up of a pair of U shaped plates 11, 11', made preferably of aluminum (see Fig. 8) and held in spaced relation by shouldered rivets 12. In the space between the plates, there is snugly fitted a filler or lower jaw liner 13, which is made preferably of Bakelite and is somewhat T shaped in cross section, i. e. having an upper face wider than the main body. Said face is preferably convex and has longitudinal ridges thereon. See Fig. 6. This liner, as shown in Fig. 10, is slightly longer than the distance between the two pairs of right angled extensions 14 and 15, which extensions comprise the arms of the U shaped base and are in the same plane therewith. The 40 ends 16 of said liner are of reduced width to fit into the space provided between said metal plates and thus fill the clearance spaces at the ends.

The plate 11 or so-called top plate, as viewed in Fig. 9, has right angled supports or brackets 17 thereon, preferably formed integrally therewith. These supports or brackets are notched at 18 to receive a member of non-circular outline, as for example a hexagonal head hereinafter described, which prevents rotation thereof. Each 60

bracket also has small notches 19, 19, as shown in Fig. 6, to receive the ends of a shield of heat insulating material 20. This shield follows the general outline of the metal U shaped plate 11 (as shown in Fig. 7), and is intended to be positioned adjacent said plate (as shown in Fig. 6) with a slight clearance between the two, as hereinafter described. One edge of the shield is toothed as at 20', the sides of the teeth being 10 beveled. The purpose of this toothed shield will be hereinafter explained more fully. Said shield is sufficiently flexible to be bent, as shown in Fig. 8, whereby its notched ends 21 may fit against the brackets 17 when the shield springs 15 back to normal position and hence locks itself against accidental removal.

The left hand end of the main jaw member, as seen in Figs. 3 and 10, has a cam member 22 pivotally mounted on a rivet 23. Part of the periphery of the cam member is knurled, as shown at 20 24, to afford a finger grip and adjacent thereto is a hole 25 to receive a pin 26 (shown in Fig. 10) to provide additional leverage. The pin used for the purpose may be the so-called arranger pin 25 which is used for certain purposes in waving hair and therefore available for this other purpose. The cam surface, instead of being formed as shown in Fig. 10, may have a series of small flat surfaces 27, as shown in Fig. 16, to increase the 30 security of the cam as a locking device. The main jaw member or receiver member has a flat, curved strip of spring metal 28 mounted between its U shaped plates 11, 11', to throw the smaller jaw open, as hereinafter described.

35 The upper jaw or smaller jaw of the clamping member, which may be called the bar member, consists of a clamping bar in the form of a light, metal channel member 30 made preferably of aluminum and pivoted at one end about a rivet 40 31, provided with a brass bushing. The head of this rivet and of rivet 23 projects slightly above the surface of the plate 11 and its extensions 14 and 15. The side of the Bakelite liner also projects beyond the surface of this plate. The 45 shield 28 bears against these projections and is then held in spaced relation to the plate 11, as shown in Fig. 6, thus providing a dead air space. The pivoted end is shaped as shown in Fig. 10 to provide a rounded shoulder 32 which is engaged by the spring 28 when said bar falls closed 50 approximately to the position shown in Fig. 4. Further closing movement puts the spring under tension, so that when said bar is released it flies open through an angle of 180°, and comes to rest. 55 The end of said upper jaw opposite the pivoted end is in the form of an extension 33 of reduced width and also inclined, as shown in Figs. 1 and 4. A rubber jaw liner 34, is provided which is somewhat T shaped in cross section throughout 60 most of its length, as shown in Fig. 14. Its ends 34', however, are of the same width as the stem of the T (Fig. 15). The stem or narrower part fits within the channel in the upper jaw member 30 and has beveled ends, as shown in Fig. 10. 65 The end extensions 34' fit between the parallel plates or lateral extensions 14, 14 and 15, 15, when the jaws are closed, thus forming a seal at the ends. Said channel member 30 has an opening 30' therein (Fig. 10) to relieve the air cushion. 70 75 which would otherwise form behind the rubber liner.

Both ends of the upper jaw, although of reduced width, are nevertheless of substantial width as compared with certain prior devices. The end which is hinged to the pivot 31 has very

little side play, therefore, and as a result the upper jaw may be readily closed by holding it in one hand and pressing downwardly on the upper member, the reduced extension 33 swinging accurately into the space between the two right angled extensions 14 and striking the cam member 22, thereby rotating the latter from its normal ineffective position, to a position where it obstructs said upper arm against return movement. When the device is held in vertical position the cam usually assumes a position in which its flat surface is diagonal, as shown in dotted lines in Fig. 4. In this position and with the upper arm normally held by the spring in about the position shown in said figure, it is easy to 10 open the jaws over the strands of hair and clamp the hair initially, i. e. close and lock the jaws, by the use of one hand only. The cam may thereafter be tightened by turning the cam with the finger or by increasing the leverage by means 15 of the pin 26 referred to. Said jaws may be readily disengaged by rotating the cam in the reverse direction with the finger or by the use of the pin, whereupon the upper jaw flies wide open, thus facilitating the removal of the clamp 25 from the tress of hair.

The jaw liners 33 and 34 clamp the hair firmly and by virtue of the rubber liner in the upper jaw, there is no clearance left between the jaws where no hair is present. In other words, the 30 rubber liner yields sufficiently to bring the rest of the jaw surfaces together, thereby avoiding a crack through which steam might leak and cause injury to the scalp. Thus there are two advantages in the use of the rubber. It prevents 35 damage which might be caused by pressing the hair against the hard Bakelite and it yields to maintain an effective seal. The rubber surface yields when the convex ribbed surface of the Bakelite liner is pressed against it and thus assumes a double reverse curve, when viewed in cross section, providing what may be called a double lock against the intrusion of hot vapor and also effecting a firm gripping of the hair but without baking a kink in the hair. The rubber liner is pressed back in the channel during 40 this clamping engagement but without meeting resistance from the confined air, because of the vent hole 30'. It will be understood that the clamp during use becomes fairly hot. The cam 45 is of such shape that it holds the jaws properly clamped regardless of the thickness of the tress of hair between said jaws. In other words, said cam provides an adjustable clamping device. Under some circumstances, and depending on the 50 shape of the inclined, apertured end 33 of the upper bar, it may be desirable to use the form of cam having flat faces 27. See Fig. 16.

As stated, the reduced ends of the upper jaw extend between the double walls 14, 14 and 15, 15, thereby occupying the available space and preventing any leakage of steam around the ends of said upper jaw.

The hair is wound on a spindle 35 which is made preferably of light material such as aluminum, said spindle being of less diameter near the middle than near the ends. As shown in Figs. 11 and 12, said spindle has a cylindrical recess in each end. The recess 35', in Fig. 11 receives a cylindrical member or spring housing 36, 70 having a head 37 of hexagonal outline or some other non-circular outline, which is locked against withdrawal, as hereinafter described. This head 37 fits into the recess 19 in the left hand one of the two brackets 17, as shown in Figs. 1 and 2. 75

- The spindle has a knurled disc 38 at the right hand end which is mounted on a shaft or stem 39 and is preferably integral therewith. The shaft or stem has a pressed fit in the end recess. Said stem has an annular recess 40 turned therein, providing a bearing which fits loosely in the right hand bracket, and providing shoulders on each side which serve as abutments to limit lengthwise movement of the spindle (see Fig. 1) when it is mounted in said brackets 17, 17. It will be understood that the spindle may be reversed end for end, in said bracket. The stem 39 is secured in the spindle by a pin 41 which serves also as a pivotal support for a clamping arm 42.
- 15 The spring housing 36 (see Fig. 11) has a helical spring 43 fitting snugly therein. A split brass bushing 44 is fitted over the other end of the spring. An end view of the spring and bushing is shown in Fig. 13, on the same scale. The bushing is made of relatively soft metal, as for example brass, and when said bushing and the associated parts are forced into the end recess 35', as a unit, said bushing is contracted about the spring and grips it to prevent rotation. The bushing itself is also held by friction against rotation and the spring housing 36 is positively locked against withdrawal by indenting the end of the cylindrical portion 46 of the spindle, into the groove 36'. However, said spring housing 30 may turn relatively to the spindle in one direction but not in the other, because the turns of the helical spring expand when the rotation is in one direction and grip the inner wall of said housing, thus forming a clutch. The arrangement described comprises a simple and effective unit assembly whereby a small spring, such as this, may be held at one end against rotation without providing positive fastening means.
- A knurled sleeve 45 is slidably mounted on the reduced end 46 of the spindle (see Figs. 1, 5 and 11). This knurled sleeve has an inner shoulder 47 which engages the shoulder 48 on said spindle. The part of the spindle immediately to the right of said shoulder 48 (in the position shown in Fig. 11) is enlarged, as shown at 49, to form a wedging surface over which the knurled ring 45 may be slid a short distance only. The purpose of this is to clamp and frictionally hold the end of the clamping arm 42, which end is reduced in width to form a tapering finger 50 (see Figs. 1 and 5) which fits over the enlargement 49. It will be seen that whereas the knurled sleeve 45 may slide freely back and forth a certain distance on the cylindrical surface 46 (see Fig. 11) when the arm 42 is swung away from the spindle 35, as shown in Fig. 5, it is limited in such movement by the shoulders 47 and 48 in one direction and by the head 37 in the other. However, when said arm is swung down to clamp the strands of hair, 60 the sleeve 45 is slid up over the enlargement 49 and over the end 50, as far as it will go, thereby providing a variable or adjustable clamp in that the arm 42 is clamped in the desired position regardless of the thickness of the tress of hair 65 between it and the spindle 35.
- With the arrangement provided it will be apparent that a tress of hair of a few strands or of considerable size may be clamped between the jaws. The spindle is then rotated by the fingers 70 while holding said spindle away from the head, to maintain the hair under tension as it is being rolled onto said spindle. It may be rolled over or under, as the patron may desire, without turning the clamp upside down. When the spindle has 75 almost reached the brackets 17, the hexagonal nut head is fitted into one of said brackets, the recessed portion 40 at the other end is fitted into the other bracket, and the rotation of the spindle continued by means of the knurled knob 38. Thus the hair is maintained under tension and such 5 final additional tension may be given to it as may be desired, as the spindle rotates with respect to the head 37, but will not rotate in a direction to release the tension, because of the spring clutch, shown in Fig. 11. The final tension given to the 10 hair may be increased by inserting the pin 26 or some other slender instrument into one of the openings 38' in the knurled knob and applying the necessary leverage.
- The arrangement of the clamping arm 42 and 15 collar 45 on the spindle is such that it is possible to roll a tress of hair over and over on itself somewhat in the form of a spiral, and of substantial thickness, which, nevertheless, will be clamped and held against slipping by reason 20 of the fact that the arm 42 is somewhat resili- 25 ent and because of the adjustment permissible in the sliding movement of the knurled collar 45 onto the flaring portion 49. The tress of hair may also be wound on the spindle from end to 25 end, if desired, i. e. in the form of a helix. In the hairdressing art the winding of the strands of hair over and over on themselves in the form of a spiral is called Croquignole winding. Winding strands of hair in the form of a helix is 30 known erroneously as spiral winding. One im- 35 portant advantage of our adjustable clamping collar over certain prior devices now in use, is that the spindle may be rotated by one hand only, in certain cases, or, what is more important, 35 it may be rotated by holding the opposite ends in the two hands and thereby maintaining the desired tension on the hair while rotating the spindle and holding it substantially parallel to the U shaped member 18, and accomplishing this 40 without slipping of the hair. With some earlier devices it has been necessary to hold the free end of the hinged arm (corresponding to arm 42) against the spindle in order to hold the hair. If the hold is accidentally relaxed the hair slips. 45 Furthermore, it has been necessary to rotate the spindle several times in order to superimpose the turns of hair over each other to produce a frictional grip, useful in preventing slipping, should the grip on the end of the pivoted arm be relaxed. With this arrangement it was also more 50 difficult to clamp the hair at the extreme end, the tendency being to clamp it some distance from the end. In other devices when short hair is wound on a spindle and only one or two turns 55 of the hair encircle the spindle with any substantial amount of tension, it is difficult to hold it. With our device very short hairs may be clamped and curled, as they may be gripped practically at the end near the head, and held without slipping as the spindle is rotated. 60
- In using the appliance the strand of hair is first drawn through a slit in the usual felt pad 51 (shown in Figs. 1 and 2) this pad being placed against the head to protect the latter 65 from the heat. After the hair is clamped, wound on the spindle and tightened, heat is applied by means of a chemical reaction or other heat sources in the usual way. The clamp is designed to protect the head as much as possible. It will 70 be noted that the two U shaped plates comprising the receiver member, are spaced by rivets, thereby providing a clearance between the two, or air space, which serves as a heat insulating means. In addition, the flexible shield serves also 75

as a heat insulator and is spaced slightly from the adjacent U-shaped metal plate to provide a further thin layer of air as an additional heat insulator.

5 Among other advantages it may be mentioned that the rubber liner, being to a considerable extent enclosed in the channel member, is protected and thus lasts longer. The flanges of the channel press the margins of the rubber liner 10 against the Bakelite surface, the central part of the rubber yielding to conform to the convex surface of the Bakelite and being pressed further into the channel member.

The device, being composed in its main elements, of three parts, i. e. the main jaw member, the auxiliary jaw member and the cam to clamp the jaws together, results in a structure which is light and which is very easy to manipulate. The device at the same time, however, 20 embodies many refinements and improvements over prior devices and it is particularly efficient in protecting the head from the heat.

If desired, the flexible shield 28 may have an auxiliary arm of rectangular outline pivoted thereto at one end thereof the general location 25 of the pivot being similar to that of the upper clamping arm 30, whereby said auxiliary arm may be swung open when the tresses of hair are being introduced between the main clamping 30 jaws and may be swung shut to serve as a shield for said clamping arm 30 when the latter is secured in closed position. Various other changes in the form and arrangement of parts may be made without departing from the spirit of the 35 invention as expressed in the appended claims.

We claim as our invention:

1. In a hair waving apparatus, a hair clamp composed of three members only, two clamping members hinged to each other, and an eccentric cam pivoted directly on one of said members and 40 pressing the other member toward clamping position when said cam is in one rotative position with a portion of said other member between it and said first mentioned member, and providing a clearance between itself and the free 45 end of said other member in another rotative position, whereby said clamping member may be swung to open position and also back again to clamping position past said cam.

2. A hair clamp comprising two elongated members, i. e. a receiver member having enlarged 50 ends and a bar member pivoted to one of said ends, a cam mounted on the other of said ends at such distance from the pivotal mounting that the free end of said bar member, in swinging to clamping position, may clear said cam when the latter is turned to the proper position and may come to rest immediately thereafter, whereby 55 rotation of said cam will cause it to engage an upper surface of said bar member and press it into clamping relation with said receiver member.

3. A hair clamp comprising a receiver member 60 formed of two plates of similar outline, with means for holding them in spaced parallel relation, a bar pivotally supported at one end between said plates, and a cam plate pivotally supported between said plates near the path of travel of the free end of said bar, whereby in one position of said cam plate said free end may engage 65 said cam plate while moving to closing position and rotate the same to a position which permits said end to pass said cam plate and whereby said cam plate may thereafter be rotated to clamp said bar against said receiver member.

75 4. A hair clamp comprising a receiver member

formed of two substantially similar plates with means for holding them in spaced, parallel relation, a clamping bar pivotally supported at one end between said plates and a cam plate pivotally supported between said first plates near the 5 path of travel of the free end of said clamping bar, whereby in one position of said cam plate said free end may engage said cam plate while moving to closing position and rotate said cam plate to clamping position.

5. A hair clamp comprising a receiver member composed of parallel plates held in spaced relation to provide ventilation therebetween, a bar member hinged between said plates near one end of said receiver member, and an eccentric cam 15 rotatably mounted between said plates on a pivot near the other end of said receiver member, said cam being so constructed and arranged as to be capable of engaging the free end of said bar member when the latter swings to clamping position between said plates and variably pressing said bar and receiver members into clamping relation.

6. A hair clamp comprising a receiver member composed of parallel plates each having lateral 25 extensions at the ends, the inner walls of said extensions being the same distance apart, means for holding said plates in fixed spaced relation, a facing member T-shaped in cross section, having its stem fitting between said plates with its 30 wider transverse portion overlying the edges of said plates and extending from one of said inner edges to the other, said member having extensions of reduced width at each end fitting between said lateral extensions at each end, a bar member hinged between said extensions at one end and fitting between the extensions at the other end, when said bar member is in clamping position substantially parallel to said receiver member, said bar member being channeled and also fitted 40 with a T-shaped member opposing said first T-shaped member whereby the wider transverse portions of said members are pressed against each other in said clamping position, one of said facing members being made of resilient material, 45 the second mentioned T-member having end extensions also, to engage the corresponding end extensions on said first mentioned T-member, between said plate end extensions, and means mounted on one of said hinged members for pressing the two members together to clamp hair 50 between said facing members and forming an effective vapor seal along the clamping faces of said members and between the end extensions thereof.

7. A hair clamping device as in the preceding claim in which said bar is of a length and breadth sufficient to substantially fill the space between said inner walls so that the clamp when closed 55 presents a positive seal against the passage of hot vapor therethrough anywhere within the periphery of said clamp.

8. A hair clamp as in claim 6 in which said bar in its main portion between said inner walls, is of a thickness substantially equal to that of said receiver member but with its ends of reduced width to fit between the lateral extensions on said plates to thereby provide a vapor seal therebetween.

9. A hair clamp composed of a receiver member 70 having a bar member hinged to one end thereof, a cam pivoted to the other end to adjustably compress said bar member against said receiver member, the latter having a non-resilient clamping face, said bar member being channeled 75

to receive a resilient member having a clamping face wide enough to overlie the edges of said channel member whereby said edges press said wider portion more firmly against the outer margins of said non-resilient face than against the center thereof, thereby affording a double vapor seal between said clamping faces.

10. A hair clamp as in claim 9 in which an opening is provided through said bar member 10 communicating with the channel therein to facilitate compression of the resilient facing member in said channel.

11. A hair clamp as in claim 9 in which the non-resilient face of said receiver member has 15 longitudinal grooves therein, said face being convex in cross section throughout its effective length so that a clamped strand of hair is frictionally gripped in a double reverse curve to firmly hold the heated hair without kinking and to increase 20 the effectiveness of the vapor seal.

12. In a hair clamp, elongated hinged clamping members having substantially straight clamping faces, and a rotatable cam mounted on one of said members to engage the other member after the 25 latter has been swung substantially to clamping position, for forcing said members toward each other into firm, clamping engagement, a spring fixed on one of said members and operating on the other, under tension, whenever during the 30 closing of said clamp, the angle between said hinged members becomes less than any predetermined angle sufficient to permit the easy introduction of hair between said clamping members, said spring being tensioned normally to hold said 35 clamping members apart at the desired angle and to throw said members apart upon release of the same from each other after compression to a lesser angle.

13. In a hair waving appliance, a U-shaped 40 receiver clamp member with an eccentric cam pivoted on one arm thereof and with a bar clamp member hinged on the other arm thereof, said bar member having, at the clamping side of its 45 free end, a bevelled tip just long enough to swing past said cam when the latter is so turned as to present its shortest radius toward the passing tip, and the bevelled surface being substantially perpendicular to the longer radii of said cam when engaged by it in clamping position, thus 50 affording a secure lock and preventing slipping or relaxation of the clamping pressure.

14. In a hair clamp, a main member, a bar member hinged thereto, an eccentric cam pivoted 55 on said main member to provide a variable pressure against said bar member, the cam surface along the contacting portion consisting of a consecutive series of short, rectangular plane surfaces each approximately perpendicular to the corresponding cam radius, to prevent reverse 60 rotation of said cam when under pressure against said bar member.

15. A hair clamp as in claim 13, in which said bevelled tip, when in clamping position, extends beyond the line of the clamping pressure from the cam pivot, and thus permits the use of shorter arms on said U-shaped receiver member without loss of locking security.

16. In a hair waving appliance, a main clamping member having arms parallel to each other 70 and perpendicular to the main clamping face at each end thereof, an auxiliary clamping member hinged on one of said arms having a clamping face to register with said main clamping face, and a cam eccentrically pivoted on the other of 75 said arms, said cam having on its periphery a

flat portion forming a chord and having an adjoining portion with a radius short enough to permit the free end of said auxiliary member to swing past it without contact, and having other portions of progressively longer radii which engage said free end when said cam is rotated and thereby press said clamping members together, said cam being so balanced with respect to its pivotal support that when said clamping members are operated in a vertical plane with the main clamping face horizontal and facing upwardly and with said flat portion facing said auxiliary member, said flat portion is engaged by said free end of said auxiliary clamping member as the latter is manually swung past said cam toward said main clamping member, thus rotating said cam and presenting said portions of progressively longer radii to said free end until the latter is engaged and said auxiliary member is automatically locked in clamping position.

17. In a hair stretching device, a clamp to hold a tress of hair near the head, a spindle on which said clamped tress of hair may be wound, a spring clamping finger hinged on said spindle and closely conforming to it, a ring on said spindle slidable over said finger to clamp the hair to said spindle, means for limiting the sliding movement of said ring away from said finger, supports on said clamp to receive and hold said spindle against reverse rotation and means associated with said spindle to permit rotation thereof in a forward direction only.

18. In a hair winding clamp, a winding spindle of varying diameter, a conforming clamp finger hinged to one end of said spindle and having a tip flared and humped to fit the correspondingly flanged portion of the spindle beneath it, and a ring slidable on said spindle and over the portions of increasing diameter of the combined finger tip and spindle to press them together 40 adjustably according to the thickness of the 35 clamped hair.

19. In combination, a round hair winding clamp consisting of a spindle of varying diameter with a clamp finger shaped to conform to said spindle and hinged at one end thereto, the tip of said clamp finger being outwardly rounded and flared in a direction toward its hinged end, and the portion of the spindle covered by said tip being correspondingly rounded, a ring slidable on said spindle and over said tip a variable 50 distance according to the amount of hair confined between said spindle and finger clamp whereby tresses of different sizes may be securely clamped, without encircling said spindle, and thereafter wound thereon by rotating said spindle, a flat 55 hair clamp composed of three members only, i. e. two hinged clamping members and an eccentric cam pivoted directly on one of said clamping members and pressing the other against it, said round winding clamp being detachably mounted on said flat hair clamp, and means for preventing reverse rotation of said winding clamp, whereby tension developed in the hair between said two 60 clamps is maintained.

20. In a hair waving appliance, a winding spindle having a clamping finger hinged thereon, a ring slidable on said spindle over the free end of said finger whereby hair positioned between said spindle and finger is firmly clamped, a knob 70 on said spindle knurled to facilitate manual rotation and having an opening therein to accommodate a lever to provide additional turning moment.

21. A hair tensioning spindle flaring in configuration from the center toward the opposite 75

- ends, a knurled disc at one end of said spindle, a non-circular head at the other end thereof, a hollow stem secured to said head, a helical spring therein projecting into a recess in said spindle, 5 and a split collar surrounding part of said spring and having a tight fit within said recess, whereby said head may be turned in one direction with respect to said spindle, but is prevented from turning in the opposite direction by the gripping 10 action of said spring within said hollow stem.
22. In a hair waving appliance, a U shaped clamping member with a bar clamping member hinged on one arm thereof, an eccentric cam pivoted on the other arm thereof to compress 15 said clamping members together in the plane of their movement, supports on said U shaped member for a detachable winding hair clamp, said supports being notched to receive a thin, flexible sheet of heat insulating material, which material 20 may be installed or detached by flexing the same, said sheet having an outline coinciding with that of said U shaped member and toothed along its inner edge to divide the clamped hair into relatively even sized tresses and obstruct the flow of 25 vapor or hot liquid down upon and through said clamping members, and a detachable winding spindle and hair clamp supported by said U shaped member.

23. In a hair waving appliance, a U-shaped

clamping member composed of separated parallel plates held fixedly apart by spacers, a bar clamping member hinged on one arm of said U member, and an eccentric cam pivoted directly on the other, so as to engage and adjustably clamp said bar against said U member, only after said bar has been swung almost to closing position, and means for winding and stretching the clamped hair and excluding hot vapors from the clamp. 5

24. A hair tensioning spindle flaring in configuration from the center toward the opposite ends, an extension at one end of said spindle comprising a handle, a non-circular extension at the other end thereof, one of said extensions 10 having a hollow stem rotatably fitting in a recess in one end of said spindle, an annular groove in said stem, a locking projection on said spindle extending into said annular groove to hold said stem against withdrawal, a helical spring, one 15 end of which is received within said hollow stem and the other end of which projects into said recess, and so constructed and arranged that upon attempted relative rotation of said spindle and said non-circular extension, said spindle may be turned in one direction, but is prevented from turning in the opposite direction by the gripping 20 action of said spring. 25
